Application May 9, 1955, Serial No. 506,876

15 Claims. (Cl. 200—38)

This invention relates to a novel motor-driven timing switch. More specifically, this invention relates to a timing device of the type described wherein two successive intervals may be timed by the same device. The structure of the present invention utilizes structural features described in a copending application Serial No. 504,254, filed April 27, 1955.

In the prior art there have been various timing switch devices for timing successive intervals of time. However, these devices have not permitted adjustment of the length of the timed periods. The present invention is an extension of devices timing successive time intervals in that it does permit timing adjustments. It is possible to change the length of one or both of the successive periods using the device of the present invention. Moreover, the present device permits timing to begin at any time in response to a signal.

In terms of broadest inclusion, the structure of the present invention employs a constant speed motor drive on a frame. A rotatable system is supported on the frame and its parts are coupled together for simultaneous rotation. This rotatable system includes first and second timing actuators and a limiting arm. Means is provided for coupling the rotatable system to the drive in response to a signal, thus enabling selective timing any time an operator wishes to put the device into operation. A spring or other resilient means is provided between the frame and the rotatable system to urge the actuators to rotate in the direction opposite that imposed by the drive. Stop means is positioned to intercept the limiting arm and consequently to limit the rotation imposed by the resilient means. First and second switches are supported on the frame in position to be actuated by the first and second actuators, respectively, in the course of rotation of the system away from the position in which the limiting arm engages the stop.

In the preferred embodiment of the present invention the actuators are placed side by side and rotate at the same speed on what is effectively the same axle. These actuators are preferably cam members, although other types of actuators, such as radial arms, could be substituted. By one of a variety of means, such as making the axle a compound member, the parts of which are mutually rotatable, one actuator is able to be rotatably or angularly adjusted relative to the other. The positioning of the actuators effects an adjustment in at least one of the successive timed periods, preferably the later period. The earlier period may then be adjusted by rotatable adjustment of the stop in order to change the "zero position" of the rotatable system. In the preferred form of the invention the stop is mounted on a rotatable member which has the same axis of rotation as the limiting arm.

In the preferred embodiment during timing, the rotatable system is driven away from its zero position. The length of the first timed period is determined by the position of the first actuator to actuate its switch relative to the stop. Since the switch is in fixed position on

2

the frame, changing the position of the stop changes the zero position of the rotatable system and hence changes the position of the actuator relative to the switch. The length of the second timed period is determined by the positions of the respective actuators. Since the switches are both fixed to the frame and do not move relative to one another, adjustment of the second actuator to actuate its associated switch relative to the position of the first actuator will change the second period timed without effecting the first. The adjustment of the timing periods may be accomplished within the scope of the present invention by various means in addition to the preferred means described. In addition to adjustment of the zero position by movement of the stop and adjustment of the relative angular positions of the actuator means, it is possible to adjust the timing of the device of the present invention by changing the position of the switch means. Various combinations of adjustments may be employed. In order to simultaneously vary the two consecutive periods, two adjustments may be made selecting two of the following: movement of the stop, movement of either or both of the actuators, or movement of either or both of the switches.

For a better understanding of the present invention reference to the drawings which show a preferred embodiment will be made. These drawings may be described as follows:

Fig. 1 is a side elevational view of the preferred embodiment with the case and certain other parts in section or partially in section;

Fig. 2 is a sectional view taken along line 2—2 of Fig. 1 showing certain parts partially broken away;

Fig. 3 is a sectional view taken along line 3—3 of Fig. 1 showing certain parts partially broken away;

Fig. 4 is a partial front elevational view wherein part of one of the knobs is broken away;

Fig. 5 is a schematic representation of the stop, the limiting arm, the two cam actuators and their associated followers which are in turn coupled to switches (not shown) in zero position;

Fig. 6 is a schematic drawing similar to Fig. 5 but showing the actuators advanced to the point of actuation of the first switch but not the second; and

Fig. 7 is a schematic drawing similar to Figs. 5 and 6 but showing the actuators advanced in position to the point where both switches have been actuated.

Referring now to the drawings, Fig. 1 gives an impression of the overall structure of a preferred embodiment of the present invention. Planar mounting decks 10, 11, 12 provide the surfaces on the supporting frame on which most of the structure of the present invention is mounted. Casing 13, which is advantageously rectangular in section, is employed to enclose much of the structure to keep it dust free. This casing in other embodiments might be made of any desirable cross section. Column 14 and a similar column on the other side of the structure separate mounting deck 10 and the planar end of casing 13 and support the casing on the mounting frame. Columns similar to column 14 are advantageously employed between each pair of supporting decks. Some such connections are required between the various portions of the support frame, of course. However, since such support members are conventional, for the sake of simplicity and clarity they have been omitted in these drawings.

The drive power of the present invention is supplied by motor 16 through gear connections within gear box 17 to drive shaft 18. Pinion 19 is fixed on to drive shaft 18. Pinion 19 meshes with a pair of oppositely disposed planetary gears 20 which are supported on diametrically opposed radial arms 21a and 21b of three armed cross member 21. Cross 21 is supported on the

end of axle 22 which lies coaxial with drive shaft 18. The direct support for gears 20 is furnished by stud shafts 23 on arms 21a and 21b. Gears 20 are rotatably mounted on said stud shafts and held in place thereon in any conventional manner. A pair of gears 24 also rotate about studs 23. One is fixed to one gear 20 on its stud so that they rotate in unison. The other gear 24 is connected to the other gear 20 through a spring 24', thereby providing an anti-backlash system for the planetary gearing, and also normally rotated in unison with it. Gears 24 in turn mesh with spur gear 25 which is free to rotate relative to shaft 18 with which it is coaxial. Gear 25 is fixed to drum 26 to rotate in unison with said drum. In the preferred arrangement illustrated, gear 25 and drum 26 are both fixed to sleeve 27 which is supported on a bearing (not shown in detail) surrounding a portion of drive shaft 18 and secured to gear box 17. A slip ring indicated generally at 27' maintains them on the bearing.

The drum 26 has a peripheral cylindrical flange, the inside surface of which is covered with material 29, such as rubber, having good frictional properties. Brake shoe 31 having the contour of this inside surface of the drum is closely spaced to said surface and arranged to be brought into contact with it. Shoe 31 is supported on a complex arm 32 and is provided with a knurled outer surface. Arm 32 is, in turn, rotatably mounted in that it is fixed to bushing member 34. This bushing is tubular and rotatable about a stud shaft 35 which is affixed to planar mounting deck 10. Arm 32 is a planar sheet metal member parallel to deck 10 having a right angle bend in it so that, as shown in Fig. 1, the arm rises vertically along one side of the structure and then extends laterally back toward the middle of the shoe where shoe 31 is supported. Spring member 33 is coiled about bushing 34 and is fixed to post 36 which is mounted on mounting deck 10 of the frame. Spring member 33 thus tends to urge mounting member 32 downward, actually in a circular path about pin 35. Hence spring 33 tends to keep the brake shoe 31 away from drum 26. Shaft 35 also provides a support post for fulcrum member 38 which provides a fulcrum for lever member 39. One end of lever member 39 lies within an opening in brake shoe supporting member 32. Its other end lies above solenoid 40. Upon energization of said solenoid, lever arm 39 pivots about fulcrum member 38 driving shoe support member 32 upward and hence driving shoe 31 into brake 29.

Lever arm 39 has a lateral extension member 41 preferably composed of an insulator affixed to its remote end adjacent the solenoid 40. This extension extends above flexible spring metal arm 42. A contact 44 is mounted on member 42. The resilience of arm 42 tends to urge it upward. Member 42 is supported between a stack of dielectric blocks 43 which, in this instance, is supported on a remote part of fulcrum member 38. Also supported by the same stack of insulators 43 is flexible metallic member 45 which is insulated from member 42. This member supports contact 46 in a position opposite contact 44. When solenoid 40 is energized and lever arm 39 moves from the position shown, contacts 44 and 46 will be closed.

Returning again to supporting axle 22 for cross arms 21, it will be seen that axle 22 and shaft 18 are not connected together but are machined to fit so that the end of axle 22 provides a bearing for the end of coaxial shaft 18. Axle 22 extends through a mounting deck 11 where it is supported in a suitable bushing and in turn extends through support deck 12. A cam member 50 is held in place on axle 22 by set screw 51. A second cam member 52 is held in place on a tubular sleeve 53 by set screw 54. Sleeve 53 in this preferred embodiment coaxially surrounds a reduced diameter portion 55 of axle 22, its end contacting a nylon washer 53' located between it and the full diameter portion of axle 22. 75

This tubular member 53 is journaled through deck 12 just as though axle 22 were a single solid piece supporting the two cams. Between cam member 52 and support deck 12, also on tubular member 53, is cam limiting element 56, which is similar to the cam members in its general shape. Cam limiting element 56 is held on tubular member 53 by set screw 57. A projection 58 from this element is provided to intercept stop 59 on deck 12 of the frame and thus effectively to limit rotation of the sleeve 53 and hence cam 52. Stop 58 is fixed relative to switch 56, since both members are supported on the frame. Thus, the immediate purpose of stop 58 is to prevent rotation of cam 52 past a point immediately beyond that at which said switch 65 is actuated.

A switch 61 is provided with a lever arm 62 which is pivotally supported in a position where its associated roller member 63 may serve as a follower of the surface of cam 50. Larger diameters of the cam will serve to depress roller 63 and hence move lever 62 against the switch operating member of switch 61. An identical switch 65 is arranged parallel to the first switch with its lever arm 66 similarly oriented to lever arm 62 and its roller 67 in position to follow the surface of cam 52. Reference to Fig. 3 will give a clearer impression of the manner in which the switch parts coact with one another. In this case the lever 66 moves against switch actuating plunger 68 of switch 65 in order to close the normally open switch. In other cases the same movement might be used to open a normally closed switch. Alternatively, the cam surface might be changed to urge the lever down most of the time and release it at the desired time of actuation.

Disc-like member 71 having a knurled edge to facilitate its rotation is secured to sleeve 53 for adjustment to various fixed positions relative thereto. Said disc-like member 71 is permanently affixed to a segment of crown gear 72. A tubular member 73 is provided with a mating crown gear edge 73a. Radial pin 74 penetrates tubular member 73 and lies slidably within a slot in member 75 which parallels its axis. Member 75 is held permanently within member 76 by means of radially extending pins 77 which are engaged within a circumferential groove in member 75. This circumferential groove makes possible relative rotation between members 75 and 76. Member 76 has a smaller inner diameter portion than member 75, which portion is threaded to engage threaded end portion 78 of axle 22. Pin 79 through axle 22 engages slots parallel to said axle and permits member 75 to be slid axially over it in order to hold members 75 and 73 in fixed angular position relative to the axle 22 and specifically to threaded part 78. Member 76 is left free to rotate, however, and is conveniently provided with a screw driver slot extending diametrically across one end so that it may be conveniently advanced on the threaded end of the axle to force members 75 and 73 axially forward until crown gear 73a and crown gear segment 72 mesh. Their meshing prevents further relative rotation between the members 71 and 73 and the associated members coupled together against rotation by pins 74 and 79 and, hence, prevents relative rotation between sleeve 53 and portion 55 of axle 22. Furthermore, crown gears fix the sleeve 53 relative to axle 22 and hence fix cams 50 and 52 relative to one another in one of a finite number of discrete positions determined by the number of teeth in gear 73a. To prevent even the slightest relative movement of shaft 22 and sleeve 53 when locked together by the above-described rather intricate assemblage of parts the forward slotted portion of member 75 and the mating portion of the rear face of the forward part of member 73 are tapered whereby when forced together the pins 74 and 79 are tightly clamped in the slots of member 75.

It will be seen from Fig. 2 that the cross-like member

21 has on its third arm 21c a shoulder 81 which cooperates with stop 82. This stop is supported on gear 83. Gear 83 is supported on axle 22 but is not fixed thereto so that it is free to rotate about axle 22 and its common axis of rotation. Since shoulder 81 is on arm 21c, which has the same axis of rotation as the gear, any position of the gear will leave stop 82 in the path of rotation of said shoulders. As may be seen in Fig. 1, a spring 84 in the form of a helix is supported on axle 22. One end of spring 84 is fixed to the deck 11 and the other end of said spring is fixed to cross 21. Accordingly cross 21 tends to rotate in the direction opposite that produced by the motor drive, as will hereafter be explained. This rotation and spring pressure urges shoulder 81 against stop 82 as appears in Fig. 2 so that arm 21c and shoulder 81 provide a "limiting arm" to limit rotation of the rotatable system.

Gear 83 meshes with gear 85 which is rotatably mounted on a stud 86, supported on mounting deck 11. Gear 85, in turn, meshes with gear 87 which is fixed to rotatable shaft 88 which extends through mounting deck 11 and into a bearing in mounting deck 12. Gear 89 is fixed to shaft 88 adjacent to mounting deck 12. It may be held in place by a set screw or other appropriate means penetrating its hub and shaft 88. Gear 89 meshes with gear 90 which is supported on rotatable shaft 91 which penetrates mounting deck 12 through bushing 92. Shaft 91 is terminated in knob 93 which is held in place on shaft 91 by set screw 94 which terminates at a flat surface of shaft 91 or by other appropriate means. The knob is also partially hollow and is provided with spring means 97 supported by an adjustable position tab 98 mounted on deck 12. Spring 97 is preferably provided with a roller member 99 which engages a serrated or scalloped inner cylindrical surface within the knob. Also within the knob is a shoulder 101 supported on a flange 102 which is rotatably adjustable about the axis of rotation of knob 93. Shoulder 101 is arranged to abut stop 103 on knob 93. The beveled surface 95 of the knob 93 is advantageously calibrated in order to be read against a mark on the exposed surface of the mounting deck 12.

A planar support 106 arranged at right angles to decks 10 and 11 between which it extends is provided with mounting flanges 106a and 106b. Flange 106b and part of support 106 are cut away in Fig. 1. Support 106, in turn, supports a mounting flange 107 having a portion fixed flat against support 106 and a portion perpendicular to support 106 and decks 10 and 11. A solenoid 108 may be supported at one end on the portion of flange 107 parallel to support 106. Mounted on the bottom of flange 107 is a stack of insulators 109 which separate and hold in place a pair of conductors 110 and 111 from which extend flexible arms 110a and 111a. These arms 110a and 111a, in turn, support contacts 112 and 113. Flange 107 also supports a thin highly flexible member 115 which, in turn, supports solenoid armature 116. The armature is an L-shaped member the base of which is fixed to flexible member 115 sufficiently far from the end of flange 107 to permit the armature 116 to move toward and into contact with the core of solenoid 108. A lever arm 118 is fixed to the armature and is provided at its remote end with an insulator post 119 which is so arranged that, upon movement of armature 116, arm 118 forces post 119 against flexible arm 110a in such a way as to close contacts 112 and 113. A stop 120 is fixed on flange 107 above the end of arm 118 to limit its upward travel when armature 116 is released.

Figs. 5-7 show schematically the operation of the embodiment described and represent various stages in the consecutive timed periods. In these figures, despite schematic representation, the same numbers are used to designate the parts as are used in Figs. 1-4. These draw-

ings will be used to describe the operation of the device of the present invention hereafter.

Referring again to Fig. 1, in actual operation of the device, the motor drives shaft 18 causing rotation of pinion 19. Pinion 19 causes rotation of gears 20 which are meshed with it. Rotation of gears 20 necessitates rotation of gears 24 which are respectively fixed to gears 20. Gears 24 in turn mesh with gear 25. The driving of gear 25 causes rotation of drum 26. No movement is imparted to axle 22. At a signal, which causes solenoid 40 to be energized, lever arm 39 is attracted to the solenoid and hence urges shoe 31 up. When shoe 31 contacts the inside surface 29 of drum 26, the high frictional properties of said surface will prevent further rotation of drum 26. Since drum 26 will not rotate, rotation of gear 25 is impossible. Consequently, the drive of pinion 19 will cause gears 24 to revolve about gear 25, thus moving cross-like member 21 in a rotational movement in opposition to the direction of rotation urged by spring 84.

The process of actuation of each of the switches may be envisioned by reference to Fig. 3. Here it will be seen that cam 52 as it rotates will eventually have a discontinuity in the form of a shoulder between larger and smaller diameters. Roller 67 on lever arm 66 will roll up this shoulder and lever arm 66 will be depressed accordingly. As lever arm 66 is depressed, actuating button 68 of the switch will also be depressed into opening or closing a circuit as desired. Actuation of the other switch advantageously occurs in the same way.

Rotation of cross arm 21, of course, produces rotation of shaft 22. Shaft 22 may be visualized as carrying limiting arm 21c and actuator member 50 and 52 on a single rigid axle as shown in Figs. 5-7. The initial or zero position shown in Fig. 5 (also shown in Figs. 1-3) is that one into which the axle 22 is urged under the pressure of spring 84. This position is maintained because of the spring pressure until shaft 22 begins to rotate. Thereafter, switch 61 will be actuated when cam 50 is rotated to the point of discontinuity at which point the cam follower 63 will be depressed as may be seen in Fig. 6. Actuation of switch 61 marks the end of the first timed period. It also marks the beginning of the second timed period. Rotation of axle 22 is continuous, of course. Finally cam 52 depresses follower 67 and actuates switch 65. This marks the end of the second period.

The type of elements employed in the practice of the present invention is not limited to those described. For example, it is possible to substitute other types of actuators for the cams. One possible substitution might be the use of rotatable actuator arms which cooperate with toggle type switches. Other such substitutions of the parts described in accordance with their particular function are intended to be within the scope of the present invention.

Although the purpose of the structure of the present invention is to time consecutive periods, the particular feature which distinguishes the present invention is the ability to adjust the length of at least one of the periods timed and preferably to independently adjust the length of both periods. In the preferred embodiment of the present invention both periods are adjustable but adjustment is so arranged that one period is easily fixed and readily adjustable whereas the other is designed to be set and retained in position for a long period of time, perhaps involving many resettings of the readily adjustable timing period.

In the preferred embodiment, setting the second period, which is the one which is relatively fixed, is accomplished by relative movement between knob 73 and dial 71. Member 76 is provided with a screw driver slot diametrically arranged across its end. A screw driver may be inserted in the slot and member 76 turned to remove it from threaded portion 78 of axle 22. The withdrawal

of member 76 also causes axial withdrawal of member 75 which is mechanically coupled to member 76 through pins 77 as previously described. Pins 74 prevent rotation of member 75, but the arrangement of the slots containing these pins in a direction parallel to the axis of rotation permits axial withdrawal of member 75. As member 75 is withdrawn, member 73 is able to be axially withdrawn itself so that the crown gear on flange 73a may be disengaged from the section of crown gear 74 on disk 71. Thus loosened, the tubular sleeve 53 supporting cam 52 may be rotated relative to axle portion 55 by rotation of disk 71. Changing the position of cam 52 with respect to cam 50 adjusts the time interval between the actuation of switches 61 and 65. It should be noted, however, that as sleeve 53 is rotated, changing the position of cam 52 relative to cam 50, it maintains the projection 58 on member 56 in the same position relative to cam 52 so that rotation past the portion of increased diameter on cam 52 is rendered impossible. The disk 71 and member 73 may be calibrated with respect to their angular position relative to one another, using a dial 125 mounted on member 71 and a suitable mark on member 73 to be compared with dial 125. The number of discrete settings is determined, as previously mentioned, by the number of teeth in the crown gear 73a. In one preferred timer, thirty seconds is the maximum length of the second period.

Adjustment of the relative positions of the cams 50 and 52 by adjustment of cam 52 will not affect the length of the initial timed period since the limiting arm and cam 50 are fixed relative to axle 22 and cannot be moved. In order to change the first timed period, the position of the stop 82 relative to the frame is modified. It should be noted that just as it is not possible to change the first period by the cam adjustment described, it is not possible to change the second period by the movement of stop 82. Since stop 82 determines the zero position of the axle 22, changing the position of the stop will have the effect of changing the starting position of axle 22 and hence of cam 50 relative to its switch so as to lengthen or shorten the period prior to the actuation of switch 61 by said cam. The adjustment of stop member 82 is simply accomplished by the rotation of knob 93. This knob is placed in an accessible place for ease in operation and is preferably placed adjacent the knob adjustment of the second period for ease in comparison. Knob 93 causes rotation of shaft 91 and hence gear 90. Gear 90 drives shaft 88 through gear 89 and gear 87 on shaft 88 drives gear 85. Gear 85, in turn, produces rotation of gear 83 on which stop 82 is mounted. Thus, stop 82 may be positioned at a variety of angular positions relative to axle 22 and the cams 50 and 52 by rotation of knob 93. In whatever position stop 82 is finally set, tab 81 on the positioning arm 21c of cross 21 will be driven against it. Since the positioning arm 21c is mounted on axle 22, it will determine the position of said axle.

Knob 93 will tend to remain in its set position because of the interaction of roller 99, which is spring connected to the frame as previously described, and the scalloped inside surface 100 of the knob 93. The roller will, of course, seek the bottom of the various scallops and, hence, each scallop defines a discrete position of the knob with respect to the frame. Since each discrete knob position defines a stop position relative to the frame, it is possible to calibrate knob positions relative to the frame to show the time which will elapse between the time the limiting arm leaves the stop and the time when the first cam to do so actuates its associated switch. The preferred way of doing this is to put a single indicator mark 127 on the frame and a scale indicating time in seconds and fractions thereof on large diameter flange 128 of the knob. In practice it is common to put the indicator mark 127 on a member 129 which permits its slight angular adjustment relative to the frame in order to make initial calibration easier and to facilitate recalibration of the de-

vice, if necessary. The support tab 98 for spring 97 holding roller 99 is advantageously made adjustable in order to permit variation in the spring tension and hence the force needed to turn the dial. Shoulder 101 which cooperates with stop 103 is also advantageously provided with a support tab the position of which relative to the frame may be angularly adjusted about shaft 91 as an axis.

In some applications of the present invention, the contact pairs are useful in auxiliary functions associated with the timing. For example, the contacts 44 and 46 which are associated with the braking structure may serve to close a circuit to start an operation which is to be timed. Since the contacts are closed by the same fast action lever arm 39 which urges the brake shoe 31 into position, this arrangement is excellent for synchronizing effects. The contacts 112 and 113, on the other hand, instead of being actuated by the mechanical action which has to do with initiating the timing period, may provide a high current switch which is closed in response to actuation of solenoid 108 through the lever system previously described. The solenoid may be energized by the closing of a low current switch, such as switch 61. Although such switch functions are contemplated, the associated wiring necessary to their functioning has not been shown or described because the wiring will be conventional. For this same reason, wiring has been omitted from the motor, solenoid and switch elements. Wiring in a practical structure of the present invention is a matter of choice consistent with good mechanical design of the structure. The general electric circuit arrangement as described and relative mechanical positioning of the components are of particular advantage, however.

An example of one application of the present invention is its use as an actuation device for aerial movie cameras which are intended to record bomb hits. The timer in such an application might be arranged so that closing of contacts 44 and 46 would release bombs. The first timed period would then be the time required for the bombs to reach the ground. At the end of this first period actuation of switch 61 would cause the contacts 112 and 113 to close in a circuit which would begin operation of the camera. The second period would be the required picture taking time. At the end of the second period, actuation of switch 65 would stop operation of the camera. The time of camera use would not need to be adjusted for each run on the target. The time for the bombs to fall from the bomber to the target, however, might vary considerably. The preferred embodiment of the invention has the advantage that this first period is able to be easily adjusted to the time calculated to elapse between the release of the bombs and their striking the target. The period of camera operation is not easily adjusted, however, so that an inadvertent change in it or an error in setting the wrong dial is unlikely. This period is set on the ground by a technician before the plane leaves on its mission.

Although for most applications the preferred embodiment will be much preferred, it is possible to modify the structure as described quite radically within the scope of the present invention. For example, instead of moving cam 52 with respect to cam 50, it is possible by moving the switch 65 about the axis of rotation to change the timing period in the same way. Also, although it is not generally desirable to move the actuator, corresponding to cam 50, which marks the end of the first period and the beginning of the second, there may be instances where its movement would be desirable to maintain the total length of the two periods constant while changing the lengths of the individual periods. This could as well be done by moving the switch 61 at a fixed radius about the axis of rotation of actuator 50. In addition all sorts of combinations of adjustments are possible in order to obtain different effects.

Many modifications of this preferred embodiment will

occur to those skilled in the art and many structures within the scope of the claims will be apparent to such persons. All such modifications and varied structures within the scope of the claims are intended to be within the scope and spirit of the present invention. For example, while the timing device disclosed has been described as a time delay relay it may with properly modified wiring be used as a repeat cycle timer in which instead of having two adjustable time intervals we would have an adjustable pulse length and an adjustable cycling period.

We claim:

1. A motor driven switch timing device comprising a frame, a constant speed motor drive on said frame, a rotatable system supported on the frame having its parts coupled together for simultaneous rotation, said system containing first and second timing actuators and a limiting arm, means coupling the rotatable system to the drive in response to a signal, resilient means urging the rotatable system to rotate in the direction opposite that imposed by the drive, stop means supported on the frame in a position to intercept the limiting arm and consequently limiting the rotation imposed by said resilient means, first and second switches supported on the frame in position to be actuated by said first and second actuators, respectively, in the course of rotation of the system away from the position in which the limiting arm engages the stop, and means for independently adjusting said first and second timing actuators relative to their respective switches whereby sequential and independently adjustable time periods may be obtained.

2. A structure as described in claim 1 wherein the stop means is mounted on a member the position of which may be changed by rotating it relative to the frame about the same axis of rotation as the limiting arm, one of the actuators is fixed relative to the limiting arm and the other actuator angularly adjustable relative to the fixed actuator.

3. A motor driven switch timing device comprising a frame, a constant speed motor drive on said frame, a rotatable system supported on the frame and containing first and second timing actuators on a common axle and a limiting arm coupled to the axle for simultaneous rotation, means coupling the rotatable system to the drive in response to a signal, resilient means urging the rotatable system to rotate in the direction opposite that imposed by the drive, stop means supported on the frame in a position to intercept the limiting arm and consequently limiting the rotation imposed by said resilient means, first and second switches supported on the frame in position to be actuated by the first and second actuators, respectively, in the course of rotation of the system away from the position in which the limiting arm engages the stop, and means for independently adjusting said first and second timing actuators relative to their respective switches whereby sequential and independently adjustable time periods may be obtained.

4. A timing device in accordance with claim 3 wherein the stop is mounted on a gear which is rotatable about the same axis of rotation as the limiting arm and which is in turn coupled to a dial remote from said gear, the positions of said dial relative to the frame being calibrated to indicate the corresponding positions of the stop relative to the frame.

5. A timing device in accordance with claim 3 wherein part of the axle consists of coaxial pieces, one of said actuators being supported on the outer tubular piece of the axle and the other of said actuators being supported at a position axially removed from said one actuator on the inner piece of the axle, and means at one end of the axle for rigidly fixing together the two pieces.

6. A timing device in accordance with claim 3 wherein the actuators may be angularly adjusted relative to one another, one of said actuators being supported on a portion of the axle which consists of a tubular member surrounding the main axle shaft and the other being sup-

ported on said main axle shaft, means at one end of the axle for rigidly fixing together the two portions, the end of the tubular member bearing a dial, and the end of the main axle shaft bearing a knob, said knob and dial being calibrated to show the relative positions of the actuators they support, and means for releasably holding the knob and the dial in fixed position relative to one another.

7. A motor driven switch timing device comprising a frame, a constant speed motor drive on said frame, a rotatable system supported on the frame coupled together for simultaneous rotation, said system containing first and second cam members constituting timing actuators, a common axle and a limiting arm coupled to the axle for simultaneous rotation, means coupling the rotatable system to the drive in response to a signal, resilient means urging the rotatable system to rotate in the direction opposite that imposed by the drive, stop means supported on the frame in a position to intercept the limiting arm and consequently limiting the rotation imposed by said resilient means, first and second switches mounted on the frame, cam followers coupling the switches to the actuators, and means for independently adjusting said first and second timing actuators relative to their respective switches whereby sequential and independently adjustable time periods may be obtained.

8. A timing device as described in claim 7 wherein the stop is supported on a member rotatable relative to the frame having its axis of rotation on the axis of rotation of the limiting arm, and wherein the axle is composed of a main shaft on which one of the cam actuators is fixed and a tubular member coaxial with said axle on which the other of said cam actuators is fixed, the tubular member being terminated at the end of the axle in a dial and the axle being terminated at its end in a knob, and means for releasably holding the knob and the dial in fixed position relative to one another to prevent relative rotation of the cams.

9. A timing device in accordance with claim 7 wherein the stop is mounted on a gear rotatable about the axis of rotation of the limiting arm, said gear being in turn coupled to a knob for remote rotation of said stop, and wherein the axle is composed of a main shaft on which one of the cam actuators is fixed and a tubular member coaxial with said shaft on which the other of said cam actuators is fixed, the tubular member being terminated at the end of the axle in a dial and the rod being terminated at said end of the axle in a knob, and means for releasably holding the knob and the dial in fixed position relative to one another to prevent relative rotation of the cams.

10. A timing device according to claim 8 in which the means for releasably holding the knob and the dial in fixed position relative to one another comprises crown gears mounted respectively on said dial and said knob and adapted to mesh with each other when said knob and said dial are moved toward each other, and means for mounting said knob on said axle for adjustment longitudinally thereof, said last-mentioned means including a threaded collar adapted to be threadably supported on the end of said axle for movement relative to the knob to urge said knob toward said dial.

11. A timing device according to claim 10 in which a tapered member surrounds the end of said shaft between said collar and said knob, said tapered member being provided with slots in its tapered portion to receive a pin extending through said axle and a pin extending through a portion of said knob and said knob having an oppositely tapered opening to receive said tapered portion of said tapered member whereby when said tapered member and said knob are urged together the pins are firmly clamped in said slots.

12. A timing device as described in claim 1 wherein the constant speed motor drive includes a planetary drive 75 gearing system comprising a driving gear adapted to be

fixedly supported by the motor drive shaft, a brakable gear member mounted for free rotation concentrically with respect to said driving gear, a driven shaft concentric with said driving gear, two pairs of planetary gears rotatably mounted on studs fixedly supported by said driven shaft, one of each pair of planetary gears meshing with said brakable gear and the other of each pair of planetary gears meshing with said driving gear, and spring means connecting the planetary gears of one pair to each other to permit relative rotation thereof against the resilient force exerted by said spring means, whereby backlash in the planetary drive gearing system is diminished.

13. A timing device according to claim 12 in which the planetary gears of one part are fixedly secured together against relative rotation. 15

14. In a motor driven switch timing device, a planetary drive gearing system comprising a driving gear adapted to be flexedly supported by the motor drive shaft, a brakable gear member mounted for free rotation concentrically with respect to said driving gear, a driven shaft concentric with said driving gear, two pairs of

5 planetary gears rotatably mounted on studs fixedly supported by said driven shaft, one of each pair of planetary gears meshing with said brakable gear and the other of each pair of planetary gears meshing with said driving gear, and spring means connecting the planetary gears of one pair to each other to permit relative rotation thereof against the resilient force exerted by said spring means, whereby backlash in the planetary drive gearing system is diminished.

10 15. A planetary drive gearing system according to claim 14 in which the planetary gears of one pair are fixedly secured together against relative rotation.
